UNITED STATES PATENT OFFICE.

HENRY ALFRED GSELL, OF PARIS, FRANCE.

MATCH-MAKING MACHINE.

1,107,060.

Specification of Letters Patent. Patented Aug. 11, 1914.

Application filed December 8, 1913. Serial No. 805,310.

To all whom it may concern:

Be it known that I, HENRY ALFRED GSELL, a citizen of the Republic of Switzerland, residing at Paris, France, have invented new and useful Improvements in Match-Making Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

In the specification of my earlier U. S. Patent 1,028,349 there is described a machine wherein the conveying device moving in a closed cycle consists of a number of slides which place themselves beneath the place of ejection of the match-making machine, in order to receive directly matches during each ejection period. After the ejection of the matches each of these slides is advanced and replaced by the next following slide, the first named slide conveying the matches gradually and step by step to the place of delivery, then moving farther forward into the receiving position. In this device a large number of slides have to be provided, since the ejection periods follow one another at very short intervals. As described in my aforesaid specification, the number of slides can be considerably reduced if the matches ejected at each ejection period are not delivered directly to the filling apparatus but are first received by a collecting member which can hold the matches of several ejection periods.

According to the present invention the device described in my aforesaid specification is so far simplified that only one slide, moving in a closed cycle is provided. In the device according to the present invention, this slide serving as a conveying device, receives the matches, collected in an intermediate member during several ejection periods, in order to deliver them, during its closed cycle to the filling magazine. During the period during which this slide performs its movement, the collecting or intermediate member receives the matches ejected during the different ejection periods. It is therefore possible to introduce as many ejection periods to the intermediate organ as will allow sufficient time for the forward move-

ment of the slide and its return into its initial position.

Two constructions of apparatus according to this invention are illustrated by way of example in the accompanying drawings, 60 in which:

Figure 1 is a front elevation of the filling device, some parts being shown in section. Fig. 1^a is a section on the line A—B of Fig. 1, Figs. 2 to 5 show diagrammatically the 65 operation of this device, and Fig. 6 shows a front elevation of a second construction of a filling device according to this invention and Fig. 7 a detail of this device.

1 indicates the carrier bars, which are advanced in a known manner by feed wheels not shown. At the rear of the group of rows of matches to be ejected there is situated the ejecting device, of which the ejecting needles 2 are shown in Fig. 1. The ejection troughs are marked 3. Directly beneath these troughs a slide 4 is arranged, on which a rail 5 extending in the longitudinal direction of same is secured and connected to rods 6, 6^a, 6^b. The lever 6^b 70 is rotatably mounted on a pin 7 and carries a roller 8, working in a cam groove in a disk mounted on the main driving shaft 9 of the device. By means of these rods 6, 6^a and 6^b the slide 4 is moved to-and-fro in 75 the guide 10 provided in the machine framing 14. Beneath the ejection trough 3 is a piston or conveying slide 11 which is provided with a rod 12. The rod 12 is provided with a roller 13 at its lower end and 80 is guided in a cross piece 15. An arm 16 of this cross piece 15 is suitably connected to the lever 17, that is rotatably mounted on the pin 7 and carries a roller 18 working in a cam groove 18^a of the disk 18^b 85 mounted on the shaft 9 in such a manner that the said cross piece can be moved to-and-fro in the guide 19 of the frame 14 by means of this lever 17. The said roller 13 works in a groove 21 of a carrier 20, the 90 rod 22 of which is guided in the bracket 23 secured to the framing 14. The carrier 20 is moved up and down by means of a rod 24 connected in a suitable manner to the piston 22, whereby the said rod 24 which is 95 rotatably mounted on the pin 25 and carries a roller 26 working in a cam groove in a disk mounted on the shaft 9, receives a rocking motion.

27 indicates the filling trough or the 110

magazine. Directly beneath this magazine is a slide 28 which like the slide 4 is provided with a cross piece 29 and, by means of the rods 30^a, 30^b, is moved to-and-fro in the guide 31 provided in the framing 14, whereby a rocking movement is imparted to the rod 30^b which is rotatably supported at 30^d and carries an antifriction roller 30^e working in a cam groove in the disk 18.
 10 In order that the matches on the conveying slide 11 shall remain in the requisite position, it is advisable to fix a back wall 32 (Fig. 1) on the cross piece 15.

The operation of the improved device is as follows: After the slide 4 serving as a collecting member has received matches from several ejection periods it is moved to the right in the direction of the arrow shown in Fig. 1, so that the matches fall on 15 to the conveying slide 11, arranged beneath the slide 4, before the beginning of this movement of the latter. Hereupon the slide 11, by means of the parts 12, 13, 20, 21, 24, 26, is moved downward whereby the slide 4 20 during this movement of the slide 11 is again brought into the normal position in which it closes the ejection trough 3 at the bottom. As soon as the conveying slide 11 has been moved down to the necessary 25 extent (see Fig. 2), it is moved so long in a horizontal direction to the right, by means of the movement of the cross piece 15, until it is situated vertically beneath the magazine 27, that is to say it is brought into the 30 position shown in dotted lines in Fig. 2. Hereupon this transporting slide 11 is raised vertically until it is situated directly beneath the magazine 27. The slide 28 usually closing the said magazine 27 at the 35 bottom, is moved to the left shortly before the end of the up stroke of the conveying slide, so that the conveying slide 11 can now introduce the matches from below into the magazine 27. The different slides assume at this moment the position shown in 40 Fig. 3, the arrangement being such that the upper edge of the slide 28 and the upper edge of the conveying slide 11, during its highest position under the magazine 27, 45 are situated together in the same horizontal plane. When the matches have been pushed into the magazine, the conveying slide 11 is moved back again, *i. e.* toward the left while the slide 28, during the return of the conveying slide, also moves with the same speed 50 and in the same direction as the latter, until the magazine is completely closed at the bottom by means of same (Fig. 4). When the slide 11 has assumed the position shown 55 in Fig. 4 in broken lines, it is lowered in the direction of the arrow and brought into the position shown in Fig. 5, and then moved farther to the left in the direction of the arrow shown in this figure. When the 60 slide 11 is again situated vertically beneath 65

the ejection part 3 it is finally pushed again into the position shown in Fig. 1 whereupon it has completed its cycle. The sequence of operation just described is then repeated.

In order to prevent friction between the inflammable heads of the matches and the reciprocating slide 28 in the described apparatus, the arrangement shown in Figs. 6 and 7 can be used, which allows of the use of the 70 device for the filling of matches that will ignite anywhere. According to this construction shown in Figs. 6 and 7 a rigid supporting plate 33 is provided on the underside of the front magazine wall 35, while the lower part of the back wall of the magazine is formed as a movable slide 34. The 75 operation of this altered modification is as follows:—The conveying slide 11 is raised in this case a little higher than the reciprocating slide 28, so that the front ends of the matches lying on the slide 11 lie above the level of the fixed plate 33. When the slide 11 assumes its highest position, the movable part 34 of the back wall of the magazine 80 pushes the matches toward the front wall 35 of the magazine (Fig. 7). On moving the slide 28 in the direction of the arrow shown in the Fig. 7 beneath the magazine 27, the heads of the matches find a firm support on 85 the fixed plate 33, so that they do not come at all into contact with the moving slide 28 and are subjected to no friction whatever so to speak. When the magazine is completely 90 closed by the slide 28, the movable part 34 of the back wall of the magazine is moved back, in order to be brought again into the 95 position shown in Fig. 6.

It is to be understood that, of course, the individual parts may be modified as regards 100 their construction without thereby departing from the nature of the present invention.

Claims:

1. In a device for removing the finished matches from a match-making machine, an 110 ejection trough arranged adjacent the discharging end of the match making machine, an intermittently moved collecting member arranged beneath the ejection trough, a filling trough arranged at a certain distance 115 from the ejection trough and a conveying member moved in a vertical plane in a substantial rectangular cycle and conveying the matches received from the collecting member to the filling trough.

2. In a device for removing the finished matches from a match-making machine, a trough for receiving the matches from the carrier bars of the match-making machine, a horizontally movable collecting slide normally closing the ejection trough at the bottom, a stationary filling trough arranged at a certain distance from the ejection trough and at substantially the same level as the latter, a single conveying slide moving in a 120 125 130

vertical plane in a rectangular cycle and introducing the matches received from said collecting slide and kept permanently in a horizontal position in the filling trough, and 5 reciprocating means arranged immediately below said filling trough.

3. In a device for removing the finished matches from a match-making machine an ejection trough, a horizontally movable collecting slide normally closing the ejection trough at the bottom, a filling trough arranged at a certain distance from the ejection trough, a single conveying slide moving in a closed cycle and conveying the matches 10 received from the collecting slide to the filling trough, a slide opening and closing periodically the filling trough in order to allow the matches to be introduced from the conveying slide from below and means for 15 moving said opening and closing slide and the conveying slide during the return movement of the latter with the same speed and in the same direction until the filling trough 20 is completely closed at the bottom by said 25 slide.

4. In a device for removing the finished matches from a match-making machine an ejection trough, a horizontally movable collecting slide normally closing the ejection trough at the bottom, a filling trough arranged at a certain distance from the ejection trough, the lower part of the back wall of this trough being movable, a rigid plate secured to the under side of the front wall of the filling trough, a single conveying 30 slide moving in a closed cycle and conveying the matches received from the collecting slide to the filling trough and means opening and closing periodically the filling trough in order to allow the matches to be 35 introduced from the conveying slide from below.

In testimony that I claim the foregoing as my invention, I have signed my name in presence of two subscribing witnesses.

HENRY ALFRED GSELL.
